UNITED STATES PATENT OFFICE.

JOHN A. HAMPTON, OF NORWOOD, MISSOURI.

STOVE.

SPECIFICATION forming part of Letters Patent No. 599,559, dated February 22, 1898.

Application filed January 2, 1897. Serial No. 617,699. (No model.)

To all whom it may concern:

Be it known that I, JOHN A. HAMPTON, a citizen of the United States, residing at Norwood, in the county of Wright, in the State of Missouri, have invented certain new and useful Improvements in Stoves, of which the following is a full, clear, and exact description, reference being had to the accompanying drawings, which form a part of this specification.

My invention relates to improvements in stoves; and my invention consists in certain features of novelty hereinafter described, and pointed out in the claims.

Referring to the drawings, Figure 1 represents a stove containing and embodying my improvements. Fig. 2 represents the same with the base and top removed and partly broken away, showing more in detail my improvements. Fig. 3 represents a vertical cross-section on the line $\alpha\alpha$ of Fig. 2. Fig. 4 represents a horizontal cross-section on the line $\gamma\gamma$ of Fig. 3.

Similar numerals refer to similar parts throughout the several views.

1 represents the base of the stove.

2 represents an outer casing, and 3 an inner casing of smaller dimensions than the outer, providing the heating-space 4 between the two.

5 represents the top of the stove, provided with the removable cover 6, having the air or draft opening 7, provided with the draft-regulator 8.

35 The inner casing 3 is provided at a suitable distance from the bottom with the fire-plate 9 and immediately above said plate has the opening 10 in the side thereof. 11 represents an opening in the side of said inner casing 40 immediately under said plate. 12 represents a series of tubes or pipes extending horizontally across said casings directly under said fire-plate 9 and vertically in the space between said casings, communicating with the atmosphere through the openings 13 in the outer casing and through the openings 14 in the top 5. 15 represents the smoke-flue, communicating with the inner casing below said fire-plate by means of the pipe 16 and provided with the elbow 17 for connection with a stovepipe in the usual manner.

The outer casing is provided near its bot-

tom with the door 18, having the draft-regulator 19.

The cover 6 being removed, the fuel is placed 55 within the inner casing and supported upon the fire-plate therein, the cover replaced, and the draft regulated by the regulator 8. It will be observed that the draft from the draft-opening 7 is downward upon and through the 60 fuel, and the plate 9 being imperforate the draft from the fuel is outward through the side opening 10 and thence back under plate 9, across the casing, and out through the pipe 16 and smoke-flue 15. Thus the tubes 12 are 65 constantly enveloped with the flame and heat from the fire and are heated to a high temperature, generating and inducing constantly a current and circulation of air through the same, and by reason of such high temperature 70 of the tubes and constant circulation of the air therethrough any disease-germs happening to be in the atmosphere are destroyed and the air in the room rendered pure and healthful, as well as an even temperature of 75 the room maintained.

By the admission of air through the regulator 19 in the door 18 oxygen is supplied to the combustion products passing over from the fuel inducing more perfect combustion 80 thereof and producing an almost entirely smokeless stove.

I am aware that a downdraft in stoves is in common use and therefore do not claim the same broadly.

What I do claim as my invention, and desire to secure by Letters Patent, is—

1. In a stove having an outer and inner casing and a smoke-flue connected with the inner casing, a fuel-chamber in the inner casing and a heating-chamber therein under the fuel-chamber arranged to provide a downdraft into the fuel-chamber, a side draft out of the fuel-chamber and a return-draft through the heating-chamber to the smoke-flue; substantially as shown and described.

2. In a stove having an outer and inner casing, a fuel-chamber in the inner casing, a heating-chamber therein under the fuel-chamber, and a smoke-flue connected with said heating-chamber, said fuel-chamber and heating-chamber having draft-openings, arranged to provide a downdraft into the fuel-chamber, a side draft out of the fuel-cham-

ber and a return-draft through said heating-chamber to the smoke-flue; substantially as shown and described.

3. In a stove, the combination with a suitable base and top, and an outer casing provided with a draft-regulator at or near the bottom thereof, of an inner casing, a fuel-chamber in said inner casing, a heating-chamber therein under said fuel-chamber, and a smoke-flue connected with said heating-chamber, said fuel-chamber and heating-chamber having draft-openings arranged to provide a downdraft into said fuel-chamber, a side draft out of said chamber and a return-draft through said heating-chamber to the smoke-flue, and a series of tubes or pipes extending across said casing through said heating-chamber and upward between said outer and inner casings and communicating at each end with the outside atmosphere; substantially as and for the purposes set forth.

4. In a stove the combination with a suitable base and top, a removable cover on the top provided with a draft-regulator, and an outer casing provided with a draft-regulator at or near the bottom thereof, of an inner casing having draft-openings on one side thereof, a fire-plate within said inner casing between said draft-openings, a smoke-flue connected with said inner casing below said fire-plate, and a series of tubes or pipes extending across said casings under said fire-plate, and upward between said outer and inner casings, and communicating through suitable openings in the top and outer casing with the outside atmosphere; substantially as and for the purposes set forth. 25 30 35
